PORTABLE FUEL DISPENSER

Frederick E. Neef, Jr., United States Army,
Detroit, Mich.

Application November 4, 1942, Serial No. 464,502

4 Claims. (CL 221—80)

(Granted under the act of March 3, 1883, as
amended April 30, 1928; 370 O. G. 757)

The invention described herein, if patented, may be manufactured and used by or for the Government for governmental purposes, without the payment to me of any royalty thereon.

The present invention relates to portable fuel dispensers; and, more specifically, to a small compact dispensing unit including an internal combustion motor, a pump, and suction and discharge hose adapted to be used in military operations for filling small containers or motorized equipment directly from a large reservoir or tank car of fuel.

It may be explained that in the use of such devices, a suction hose is extended from the fuel dispensing unit into a tank car or other fuel supply and the engine and pump of the unit serve to draw the fuel through the dispenser and deliver it under pressure through one or more discharge hose lines and dispensing nozzles. It will be understood, of course, that in operations of this character, it is essential that the dispenser unit be sufficiently small and compact and of light weight so that it may be easily moved from place to place manually, as well as by power; and also that it is essential that the unit be so constructed as to be extremely rugged and not subject to accidental damage due to rough handling or other physical abuses. Further, it will be understood that in any type of equipment used in military operations there is considerable likelihood of damage by impacts during loading or unloading operations; and, it is, therefore, desirable to have the essential mechanisms of the device, namely, the internal combustion engine and fuel pump, well protected against accidental damage.

It is, accordingly, the principal object of the present invention to provide a light, compact portable fuel dispensing unit, including a fuel pump and internal combustion engine, together with a frame and hose cage arranged to surround the pump and engine and to provide these parts with maximum protection from external impacts.

A further object of the invention is the provision of a portable fuel dispensing unit, including a frame structure arranged to include marginal hand rails to facilitate manual carrying or shifting of the unit, and also arranged to include an internal motor cage surrounded by an external hose cage so that the coils of hose will surround the motor and pump, and offer maximum protection to these mechanisms.

A further object of the invention resides in the provision of a portable fuel dispensing unit as described above, wherein the hose cage is open at the top to permit easy removal or replacement

of the suction and discharge hose, and the motor cage is open at the bottom to permit the motor or fuel pump to be easily and quickly removed from the frame for repair or adjustment without the necessity of uncoiling the hose.

Referring now more particularly to the drawing attached to and forming a part of the present specification:

Fig. 1 is a perspective view of the present preferred embodiment of this invention, showing the manner in which the suction and discharge hose lines of the unit are coiled within the hose cage.

Fig. 2 is a central sectional view through the dispensing unit.

The frame of the unit consists of two inverted U-shaped end members, each comprising of a horizontal carrying rail 11 and two vertical corner posts 12 extending downwardly from the carrying rail to the ground. The end frames are joined at their upper ends by a pair of side carrying rails 13 and at their lower ends by a pair of base rails 14. The base rails 14 are joined by a pair of motor support rails 15 spaced inwardly from one end of the frame and a pair of pump support rails 16 spaced inwardly from the opposite end of the frame. These rails 15 and 16 serve to support an internal combustion engine 17 and a liquid fuel pump 18 as will appear more fully hereinafter.

As thus far described, the frame is of generally rectangular configuration, having corner posts at each of its corners and a continuous, generally rectangular carrying rail around its upper edge, consisting of the end rails 11 and the side rails 13, so that the entire device may be easily lifted manually and shifted from place to place.

It may be incidentally pointed out also that although the lower base rails 14 are at the outer extremities of the frame, the cross rails 15 and 16 are spaced inwardly from the ends so that some clear space is provided immediately below the end carrying rails 11. This is not an essential feature of the invention, but it is of some value in that it permits easy removal of the motor and pump from the frame, and also in that it provides for more convenient carrying of the device by the end rails 11, so that when the device is so carried there is no structure to interfere with the natural walking pace.

The frame structure also includes a relatively small rectangular motor cage located in the central part of the frame just described and arranged to enclose and give protection to the internal combustion motor and fuel pump of the device. The

motor cage also cooperates with the main frame to define an open-topped rectangular hose channel in which the suction and discharge hose lines of the device may be coiled. The motor cage consists, in general, of two end frames 21 joined by top rails 22 spaced apart by a cross rail 23. Each of the end frames 21 includes a horizontal top portion, vertical corner posts 24 extending downwardly from the top portion, and a horizontal section 25 extending angularly outwardly to one of the corner posts 12 of the main frame. The motor cage also includes a pair of generally U-shaped side elements having inside vertical sections 26 secured to the side rails 22 between the opposite ends of the rails, the sections 26 extending downwardly a distance equivalent to the downward extent of the sections 24, and then curving outwardly to form a horizontal section 27 and upwardly into a vertical outside side rail 28. The side rail 28 is in alignment between the corner posts 12 of the outside frame and its upper end curves inwardly as indicated at 29, where it is joined to the midpoint of one of the side rails 13. Thus, the inside motor cage and the outside frame of the structure cooperate to provide a generally rectangular, open-topped hose channel, so that when the hose lines 31 and 32 are coiled into the channel, they will surround the motor cage and thus give a large degree of protection against impacts to the motor 17 and the pump 18.

In addition, since the hose channel is of greater length than its width, the natural resilience of the coiled hose will tend to force it outwardly to bear firmly against the side rails 28 of the frame. The rails 28 thus will act as side limits to maintain the hose entirely within the confines of the outer frame of the mechanism and the tendency of the hose lines to exert pressure against the side rails 28 is utilized to maintain the hose in position in the frame by curving the upper ends of the frame inwardly at 29 so that the hose will be secured below the side rails 13. Thus the hose will tend to be self-maintaining in the hose cage unless intentionally removed for use. If desired, however, retaining straps 33 may be stretched between the side rails 22 of the motor cage and the side rails 13 of the main frame to tie the top loops of the hose and prevent any shifting of the hose lines.

As hereinbefore pointed out, the coil of hose around the internal combustion motor 17 and the pump 18 will protect the delicate parts of the mechanisms against accidental damage; but, at the same time, the delicate parts of the mechanisms are readily accessible for adjustment or repair by removing the hose from the hose channel, or by loosening the motor and pump from the rails 15 or 16, respectively, and removing it for adjustment independent of the frame assembly.

From the foregoing it will be apparent that by practice of the teachings of the present invention, a fuel dispensing unit may be provided that combines the obvious advantages of light weight, rugged construction, and ease of manipulation and operation; together with ease of adjustment of the essential mechanisms of the unit. In these features the preferred embodiment of the present invention illustrated in the drawing accompanying this specification are believed to represent the most desirable arrangement of structures, but it is recognized that the invention is capable of some variation and modi-

fication without departing from the spirit of this application as defined by the appended claims.

Having thus described my invention, what I claim as new and desire to secure by United States Letters Patent is:

1. In a portable fuel dispenser, in combination, fuel dispensing devices including an internal combustion engine, a fluid pump coupled to said engine, together with suction and discharge hose lines coupled to said fluid pump; said devices being mounted on a frame consisting of a marginal top rail, vertical corner posts, and a base comprising longitudinal and transverse rails; together with a motor cage consisting of a rectangular marginal top rail and vertical corner posts, said motor cage being smaller than the aforementioned frame and centrally located therein; horizontal rails interconnecting said cage and said frame, and a central side rail secured to the mid-point of the top rail on each side of the frame, each side rail extending outwardly, downwardly, and inwardly to the cage, the cage and frame defining an open-topped, generally rectangular hose channel of length in excess of its width and of a maximum width in excess of the spacing of the top rails of the frame, so that the loops of hose coiled within said hose channel will bear against central side rails of the frame and so that the resiliency of the hose will urge the hose into pressure engagement with said vertical side rails and thus maintain the hose in coiled position within the aforementioned channel, the arrangements being such that the fuel dispensing mechanisms within the said motor cage are surrounded by the convolutions of the hose and thus protected against accidental damage.

2. In a portable fuel dispenser, in combination, fuel dispensing devices including an internal combustion engine, a fluid pump coupled to said engine, together with suction and discharge hose lines coupled to said fluid pump; said devices being mounted on a frame consisting of a marginal top rail, vertical corner posts, and a base comprising longitudinal and transverse rails; together with a motor cage consisting of a rectangular marginal top rail and vertical corner posts, said motor cage being smaller than the aforementioned frame and centrally located therein; rails interconnecting said cage and said frame so that the cage and frame define an open-topped, generally rectangular hose channel of length in excess of its width together with a strap extending between the top rail of the frame and the top rail of the cage to secure the hose in coiled position within the aforementioned channel, the arrangement being such that the fuel dispensing mechanisms within the said motor cage are surrounded by the convolutions of the hose and thus protected against accidental damage.

3. A hose reel comprising a frame consisting of a marginal top rail, vertical corner posts, and a base comprising longitudinal and transverse rails; together with a cage consisting of a rectangular marginal top rail and vertical corner posts, said cage being smaller than the aforementioned frame and centrally located therein; horizontal rails interconnecting said cage and said frame, and a central side rail secured to the mid-point of the top rail on each side of the frame, each side rail extending outwardly, downwardly, and inwardly to the cage, the cage and frame defining an open-topped, generally

rectangular hose channel of length in excess of its width and of a maximum width in excess of the spacing of the top rails of the cage, so that the loops of hose coiled within said hose channel will bear against central side rails of the frame and so that the resiliency of the hose will urge the hose into pressure engagement with said vertical side rails and thus maintain the hose in coiled position within the aforementioned channel.

4. A hose reel comprising a frame consisting of a marginal top rail, vertical corner posts, and a base comprising longitudinal and transverse

rails; together with a cage consisting of a rectangular marginal top rail and vertical corner posts, said cage being smaller than the aforementioned frame and centrally located therein, 5 the cage and frame defining an open-topped, generally rectangular hose channel of length in excess of its width, so that loops of hose may be coiled within said hose channel, together with a strap extending between the top rail of the 10 frame and the top rail of the cage to secure the hose in the channel.
